STAPLER

John F. Cavanagh, Providence, R. I., assignor to
Speed Products Company, Inc., New York, N. Y.,
a corporation of New York

Application August 16, 1947, Serial No. 769,024

10 Claims. (Cl. 1-3)

1 This invention relates to improvements in stapling devices commonly utilized for fastening together paper and other sheets, for securing tags and labels to articles, for tacking printed matter to bulletin boards, and in general for various fastening or stitching purposes.

The primary object of my invention is to provide a portable fastener of simple and compact design which will efficiently staple together sheets of paper, cloth and the like and also function as a tacker.

Another object is to provide a fastener-apply ing implement adapted to be readily operated by thumb pressure while held in one hand.

Another object is to provide a fastener-apply ing device having a staple clinching member which can be swung laterally to permit the device to be used as a tacker.

Another object is to provide a device having a U-shaped sheath for the forward end of the staple magazine to act as a closure and also as a guide for the staple driver.

Further objects and advantages of my device will become apparent as this description proceeds.

In the accompanying drawings wherein I have illustrated a preferred embodiment of my invention:

Figure 1 is a side elevation view of my device, shown partly broken away.

Figure 2 is a perspective view showing how my device may be operated in fastening together of several sheets of paper or the like.

Figure 3 is a side view of my device with the clinching arm swung back to permit the device to be used in tacking operations.

Figure 4 is a plan view showing the staple driving arm swung at right angles to the stapler body to permit removal of the pusher assembly for loading a stick of staples into the rear end of the staple magazine.

Figure 5 is a plan view of the pusher assembly, removed from the device.

Figure 6 is an end view of the rear end of the staple magazine shown in Fig. 1, showing the end plate of the pusher assembly locked to said staple magazine.

Figure 7 is a perspective view of the front sheath of the magazine.

Figure 8 is a fragmentary perspective detail of the forward end of the staple driving arm.

Figure 9 is an enlarged plan view, partly in sec tion, of the forward end of the staple magazine, and

Fig. 10 is an enlarged fragmentary view on the line 10-10 of Fig. 1.

2 Referring to the drawings I have indicated at 10 a staple magazine, preferably of sheet metal, formed in rectangular channel shape and with inturned longitudinal flanges 11, as indicated in 5 Fig. 6 and Fig. 9, so as to slidably hold a stack of attached staples S and positively confine said stack against lateral and upward displacement.

Referring to Figs. 1 and 9, it will be seen that the forward end of the staple magazine 10 is provided with an upturned lip 12, for a purpose to be later explained, and that the side walls 13 of staple magazine 10 extend beyond lip 12 a distance substantially corresponding to the thickness of a staple, while the foremost ends of flanges 11, are flush with the outside surface of lip 12.

Suitably attached to the forward end of staple magazine 10 is a U-shaped sheath 14 (detailed in Fig. 7) which provides with the side walls 13 and lip 12 of magazine 10 a staple chute or throat T.

Associated with staple magazine 10 is a staple driving arm generally denoted 15, preferably made of spring steel and preferably formed at 25 its forward end as shown in Fig. 8. The thickness of arm 15 is considerably greater than the thickness of a staple and hence the staple driving end of said arm is reduced in thickness as at 16 to dimensions which permit its free entry into the 30 staple receiving throat T, sheath 14 being provided with extended portions or stop shoulders 17 of such interior width as to form a guide for the staple driving end of arm 15.

The rear end of arm 15 is provided with the 35 arcuate portion A to cover the rear end or part of staple magazine 10 and has its lower complement or branch L pivotally or movably attached to the under side of said staple magazine by rivet 18 in such manner as to permit 40 staple arm 15 to swing at right angles to staple magazine 10 (see Fig. 4), after the staple driving end 16 of said arm is raised from its normal position within said staple magazine and lifted clear of the sides thereof.

45 Slidable longitudinally within staple magazine 10 is a staple pusher 19 (see Fig. 5), preferably formed from sheet metal. Pusher 19 is slidably mounted upon pusher rod 20. It slides freely within staple magazine 10, and is prevented from 50 upward disengagement therefrom by the in turned flanges 11 of said tube.

Mounted between the pusher and the fixed end plate or stop 22 upon pusher rod 20 is a normally expanded hélicoïdal pusher spring 21 for normally urging the slidably guided pusher forwardly, that is, towards throat T. End plate 22 is rigidly at-

tached to the rear end of rod 20 and as shown in Fig. 6, is substantially of T shape so as to removably engage within and be retained by notches 23 (see Fig. 4) in the top portions of the side walls 13 of magazine 10. When arm 15 is in its normal position for driving staples (see Fig. 1) said arm prevents end plate 22 from disengaging or unlocking from the notches 23 in staple magazine 10.

Pivottally attached to the under side of staple magazine 10 by rivet 24 is an offset swingable clincher bar or base 25, provided at its forward end with conventional staple clinching recess means 26 in alinement with the driving end of staple driving arm 15. The opposite end of clincher base 25 is provided with a detent 27 (see Fig. 1) which engages a hole 28 (see Fig. 10) in the bottom of staple magazine 10 for the purpose of holding clincher base 25 in proper alignment with the staple driving end of arm 15 when the device is used in stapling operations.

In loading my improved stapling device, the forward end of arm 15, that is, its upper complement or reach U is slightly raised from engagement with, namely, removed from the staple magazine 10 and thereafter swung laterally to the position shown in Fig. 4. End plate 22 is then disengaged from notches 23 of staple magazine 10, and the pusher assembly, shown in Fig. 5, is withdrawn rearwardly and out of the magazine. A stack of attached staples S is then slid into the rear end of staple magazine 10 and the pusher assembly is reinserted into said magazine behind said stack of staples. End plate 22 is then interlocked with the walls of the notches 23 of staple magazine 10 and driver arm 15 is swung back and restored in the magazine whereby its forward end is again slidably guided in the throat or staple raceway T.

Should it be desired to use the implement for tacking operations, such as attaching posters to board surfaces, clincher offset base 25 is swung rearwardly to the position shown in Fig. 3 when staples may be driven into wood or the like by striking the driving end of staple driving arm 15 with the heel of the palm of the hand.

It will be seen that my improved stapling device is of compact design so as to be readily carried in the pocket, and that its construction permits it to be readily converted from a stapler to a tacker. It will further be seen that my fastener-applying implement is positive and reliable in action accurately guides the feed of the staples, and is easy to reload, thus meeting all the requirements for a portable stapling tool of high utilitarian value.

By the present arrangement the resilient staple driving arm 15 is normally in a raised position as indicated in Fig. 1 with the blade 16 thereof just slightly above guide lip or race block 12 to permit reception of the foremost staple of the stack S into the throat or raceway T due to the action of the slideable pusher or follower 19 which is prevented from removal from the forward end of rod 20 by the upset end E (Fig. 5).

As previously stated, base 25 pivots on the fixed fulcrum pin 24 fastened to the bottom wall of the magazine. Specifically however this base is also detachably locked to the base due to the action of struck out detent 27 snapping into aperture or opening 28.

With the driving blade 16 slidably guided in sheath 14, the latter is prevented from rotation relative to the magazine although the blade 16 may be downwardly displaced to eject the foremost staple from the throat upon the application

of a downwardly directed pressure on the biased or upper component U of the one piece operating arm 15 which is normally held in a raised position by the arcuate or externally convex and internally concaved bridge portion A, integrally merged with the upper and lower components or reaches U and L which closely straddle the open rear end of the magazine.

While I have disclosed a preferred embodiment of my invention, it will be understood that various modifications in its construction may be made within the spirit and scope of my invention as defined by the appended claims.

I claim:

1. In a fastener-applying implement, a magazine having staple guiding means defining a throat at one end and having an opposite end open, a resilient staple-driving arm mounted upon said magazine and normally straddling said open end, and means whereby said driving arm may be laterally displaced relative to said magazine for enabling a supply of staples to be inserted into said open end.

2. In a device of the character described, a staple magazine adapted to slidably receive a stack of attached staples and having a staple-discharge throat across one end thereof and an open but opposite end, a staple pusher slidable longitudinally within said magazine, and a staple driver having a driving end alined with said throat for severally driving said staples, said driver having means straddling said open end and having branch means disposed along a lower wall of said magazine, means pivotally holding said branch means to said magazine to provide for bodily displacement of said arm laterally of said magazine.

3. In a device of the character described, a tubular staple magazine adapted to slidably receive a stack of attached staples and having a staple-discharge throat across one end thereof and provided with an opposite open end, a staple pusher assembly comprising a rod, a member slidable within said magazine on said rod, a locking member attached to said rod adapted to be removably retained by said magazine, a staple driver along the upper part of said magazine and having a depending end adapted to drive staples from said throat and having an arcuate portion straddling said open end, means movably attaching a lower part of said driver to said magazine, and said driver constituting means guarding said locking member against removal from said magazine.

4. In a stapling machine, a magazine having a bottom wall and spaced sides defining a channel for slidably guiding a stack of staples, means at the forward end of said channel and characterizing a staple raceway, spring controlled follower means for urging said stack towards said raceway; driving means comprising an upper component above said channel and including depending means liftable into and out of said magazine and slidably guided in said raceway for ejecting a staple from the latter, a lower component disposed along the bottom wall of said magazine; and bridge means about the rear end of said magazine integrally interconnecting said upper and lower components; and means movably holding said lower component to said bottom wall.

5. In a stapling machine, a magazine having a bottom wall and spaced sides defining a channel for slidably guiding a stack of staples, means at the forward end of said channel and char-

acterizing a staple raceway, spring controlled follower means for urging said stack towards said raceway; driving means comprising an upper component above said channel and spaced from said sides and extending beyond the rear end of said magazine and including depending means liftable into and out of said magazine and slidably guided in said raceway for ejecting a staple from the latter, a lower component disposed along the bottom wall of said magazine, and arcuate bridge means about the rear end of said magazine and integrally interconnecting said upper and lower components; and means pivotally holding said lower component to said bottom wall.

6. In a stapling machine, a magazine having a bottom wall and spaced sides defining a channel for slidably guiding a stack of staples, means at the forward end of said channel and characterizing a staple raceway, spring controlled follower means for urging said stack towards said raceway; one piece resilient driving means comprising an upper reach above and overlying said channel and extending beyond the rear end of said magazine and including depending means liftable into and out of said magazine and slidably guided in said raceway for ejecting a staple from the latter, a lower reach disposed along the bottom wall of said magazine; and outwardly convex and inwardly concaved bridge means about the rear end of said magazine and integrally interconnecting said upper and lower components; and means pivotally connecting said lower component to said bottom wall for bodily swinging said driving means to one of said sides when said depending means has been lifted out of said magazine.

7. In a stapling machine, a magazine for supporting a stack of staples, a one piece U shaped member straddling said magazine comprising a biased upper reach sloping forwardly and upwardly away from and above the rear part of said magazine, a lower reach for supporting said magazine, curved bridge means integrally connecting the rear ends of said reaches for normally holding said upper reach elevated, means movably securing said magazine to said lower reach, and a driving blade integral with said upper reach and depending from the front end thereof for expelling the foremost staple of said stack from said magazine.

8. In a stapling machine, a magazine for supporting a stack of staples, a one piece U shaped and relatively thin sheet metal member straddling said magazine comprising a biased upper reach sloping forwardly and upwardly away from and above the rear part of said magazine, a lower

reach for supporting said magazine, outwardly convex and inwardly concaved bridge means about said rear part and integrally connecting the rear ends of said reaches for normally holding said upper reach elevated, means movably securing said magazine to said lower reach, and a driving blade removably associated with said magazine and integral with said upper reach and depending from the front end thereof for expelling the foremost staple of said stack from said magazine.

9. In a stapling machine, a magazine for supporting a stack of staples, a one piece U shaped member straddling said magazine comprising a biased upper reach sloping forwardly and upwardly away from and above the rear part of said magazine, a lower reach for supporting said magazine, curved bridge means about said rear part and integrally connecting the rear ends of said reaches for normally holding said upper reach elevated, a driving blade integral with said upper reach and depending from the front end thereof for expelling the foremost staple of said stack from said magazine, and means pivotally securing said magazine to said lower reach to allow swinging of said member bodily and laterally of said magazine.

10. In a stapling machine, a magazine for supporting a stack of staples, a one piece U shaped member straddling said magazine comprising a biased upper reach extending substantially the entire length of said magazine and sloping forwardly and upwardly away from and above the rear part of said magazine, a lower reach for supporting said magazine, outwardly convex and inwardly concaved bridge means about said rear part integrally connecting the rear ends of said reaches for normally holding said upper reach elevated, means pivotally securing said magazine to said lower reach to permit said magazine to be swung laterally of said member, and a driving blade integral with said upper reach and depending from the front end thereof for expelling the foremost staple of said stack from said magazine.
